Primary Examiner — T. Chase Nelson*Assistant Examiner* — Mark Cavanna(74) *Attorney, Agent, or Firm* — Sheridan Ross P.C.**CLAIM**

The ornamental design for a baby movement indicator, as shown and described.

DESCRIPTION

FIG. 1 is a perspective view of the baby movement indicator showing our new design wherein a plurality of items are shown floating in a contained media;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines in the figures show environment for illustrative purposes only and forms no part of the claimed design.
